UNITED STATES PATENT OFFICE.

ALBERT KRAUTH, OF HAMILTON, OHIO.

PAPER FEEDING AND SEVERING MECHANISM.

1,119,180.

Specification of Letters Patent.

Patented Dec. 1, 1914.

Application filed February 27, 1913. Serial No. 751,048.

To all whom it may concern:

Be it known that I, ALBERT KRAUTH, a citizen of the United States, residing at Hamilton, in the county of Butler and State 5 of Ohio, have invented certain new and useful Improvements in Paper Feeding and Severing Mechanism, of which the following is a specification.

My invention relates to paper feeding and 10 severing mechanism in which invariable constant lengths are successively advanced and severed from a continuous sheet.

The severing mechanism herein disclosed is in close proximity to the feeding mechanism so as to reduce the spacing interval dividing the text lengths to a minimum, and the feeding and severing accomplished in a continuous cycle of a manually operated crank handle. The paper feeding mechanism 15 becomes dormant after the prescribed advancement of the paper, with the severance of the paper progressively followed in each manipulating cycle, and provision is made for absolutely determining the cycle 20 by positively limiting its progress.

One object of my invention is to provide a pair of cutter members, one having its cutting edge longitudinally spiral and circumferentially movable so that its edge will 25 progressively engage in a tangent plane with the cutting edge of the second cutter relatively stationary and in a diametric plane with the axis of said movable cutter member. The movable cutter member in 30 its cutting operation moves counter to the direction of paper feed and thereby avoids any paper pulling action which may have a tendency to displace the alinement between several sheets simultaneously fed in text 35 registry.

Another object of my invention is to provide an oscillating cutter member with its cutting edge movable progressively in a transverse plane across the cutting edge of 45 a relatively stationary cutter member yieldingly urging its cutting edge in a diametric plane toward the axis of the oscillating cutter member.

Another object of my invention is to 50 combine paper-feeding and paper-severing mechanism arranged in close proximity to each other and with the cutting mechanism operated intermittent to operate after a prescribed interval of paper feed so as to 55 sever a continuous sheet into constant in-

variable lengths. In the disclosure herein the prescribed interval length and severance is accomplished in a complete single continuous revolution of a crank handle, with provision made definitely determining the 60 limit of a revolution, or cycle, requiring manual release for a successive operation. This absolutely determines the length of 65 interval delivery in relation to a fixed text arrangement preprinted upon the continuous sheet, in successive multiple numbers, for an invariable constant length successive delivery. The feed of the paper automatically discontinues in advance of the 70 operation of the severing mechanism in each cycle of the crank handle.

The features of my invention will be more 75 fully disclosed in the description of the accompanying drawings, forming a part of this specification, in which:—

Figure 1 is a mutilated side elevation of the forward portion of a manifolding apparatus, containing my improved paper severing and feeding mechanism with parts illustrated in section for clearer observation. Fig. 2 is a central vertical section through the machine. Fig. 3 is a detailed side elevation of the upper forward portion of the machine opposite to that shown in Fig. 1. Fig. 4 is a perspective view of 85 the cutter.

1 represents the base of the machine, upon which the side frames 2, 3, are secured. These side frames may be of two-part form, with the forward portions unitarily connected and swingingly mounted, adapting the same to be swung upon the rear portions of the side frames for convenient access to the supply webs of paper, such construction being common in machines of this type, but 90 for the purposes herein are each shown as of a single unit. Three webs of paper 4, 5, and 6 are herein illustrated, each mounted between elastic supports α secured to the side frames for rotatively supporting the 100 webs, with the supports accessible from the exterior of the machine, to withdraw the same from their web engagement, offering convenience for renewal. The continuous sheets from each of the webs pass respectively over the guide rolls 7, 8 and 9 journaled in the side frames and disposed at the receiving end of the writing table 10, over which the sheets move unitarily, one over the other and between which manifold- 110

2
ing or carbon paper, not shown, is inserted for multiple records of each entry.

The parts thus described are common in all machines of this class, and are more or less subsidiary to the features of my invention, reference being made thereto for the purpose of readily understanding the operation of the apparatus.

It is desirable to advance the continuous sheet requisitely within a complete rotation 10 of the crank handle in a manual operation of the machine and within such cycle of operation, and toward the limit thereof discontinue the feed following with a severing operation for separating the advanced end length from the continuous sheet or strip, the feeding and severing operation being all accomplished with a definite cycle of crank handle manipulation, after which 15 the crank handle is arrested but is capable of being released for a successive operation. This, however, is only essential or beneficial when one or more of the continuous strips are subdivided into equal interval lengths, 20 with the severance made at a point separating the intervals so that an improper severance cannot be made, as would occur if the crank handle were free to be continuously 25 rotated without interruption.

30 11 represents a lower paper feeding roll having its axle 12 journaled in the side frames 2, 3, with a gear 13 fixed at one end of the axle 12, inside of the casing 2 formed by the side frames. The gear 13 is in mesh with a pinion 14 fixed upon the axle 15, which carries the upper feeding roll 16. The upper feeding roll is journaled in slide blocks 17 slidably mounted in ways, one formed in each of the side frames, for 35 yieldingly journaling said upper feeding roll so as to urge its periphery into engagement, or toward the periphery of the lower feeding roll, for impingedly or frictionally engaging the paper threaded between said 40 rolls to propel or advance the paper upon rotation of the rolls. The gearing for said rolls positively rotates the same in relative reverse directions to prevent any slippage of the upper roll or movement in a direction reverse to the travel of the paper. 45 This construction of paper feeding roll is however well-known in the art, and comprises the most substantial and efficient form of paper feeding mechanism for use in mani- 50 folding devices, and in the term "paper feeding mechanism" analogous or equivalent constructions are herein comprehended.

The axle 15 of the upper feeding roll has a pinion 18 fixed thereon, preferably exterior of the side frame 2, see Fig. 3, which intermeshes with a mutilated gear 19 fixed upon the shaft 20, the shaft 20 extending across the side frames and journaling therein. The gear 19 has a portion of its teeth 65 cut away, so that the feeding rolls will be

brought to rest during an interval of a complete rotation of gear 19 to stop the paper feed for a subsequent operation of paper severing mechanism within a cycle or one complete rotation of the gear 19, or to bring the paper advance to rest during a severing interval. In the construction disclosed, an interval advance of the paper and its severance from the continuous sheet is contemplated within one cycle of the crank handle. Such operation, however, possesses the advantage in certain particular uses, and I do not wish to be limited herein to the control and operation of the paper feeding and severing mechanisms within a cycle or prescribed movement of the propelling mechanism, nor do I wish to limit myself to a discontinuance of feed during a paper severing operation, for it is obvious that the paper cutting instrumentalities could be operated under an accelerated movement over the feed or advance of the paper without interference.

In a specific use of the apparatus for feeding and severing definite lengths of pre-printed text comprised in multiple numbers in a continuous sheet, and wherein it is desirable to bring each interval or length to a definite location prior to severing the same from the continuous sheet, it is advantageous in a manually operated machine to interrupt or arrest the propelling mechanism after an interval functioning cycle, so that the operator will not be required to observe the advance of the paper or the propelling mechanism for a proper operation of the machine, and this is accomplished by the following mechanism:—21 represents a crank handle fixed to the shaft 20, having its crank arm of two-part form, one part tubular and the second part 22 slidably mounted within the tubular portion, upon which the handle 23 is fixed. 24 represents a spring mounted within the tubular portion of the handle and engaging the part 22 for maintaining the handle 23 in a normal outward position, away from the crank axis, so that a lug 25 shown in dotted lines, Fig. 1, projecting from the part 22 of the crank arm will engage a stop lug 26 projecting from the side frame 3, the engagement between the lugs arresting further propelling movement of the crank handle after each complete rotation and release from such engagement by moving the handle 28 toward the crank axis, until the lugs clear each other.

Severing mechanism.—The severing mechanism herein illustrated comprises an oscillating knife bar having its longitudinal cutting edge in a diametric plane, and spiral or angular longitudinally so as to progressively engage, with the longitudinal straight edge of a companion cutter bar yieldingly urged toward the oscillating cutter bar or knife. The cutting edge of the stationary cutter bar is in

a diametric plane with the axis of rotation or oscillation of the movable cutter blade, producing a shear action from one end of the cutter bar toward the other. The paper is fed between the cutter members with the rear portion of the stationary cutter inclined upwardly to offer clearance for the paper and guide the same between the cutters. The rearward circumferential portion of the oscillating cutter member is also provided with relief, and by reason of its spirality, the two cutter members progressively engage in a diametric line from the axis of the oscillating cutter. This has self-sharpening tendencies and avoids mutilation of the cutting edges.

The lower cutter, as above referred to comprises a cutting bar 27 having a spiral bend longitudinally from one end to the other by twisting the bar slightly with the cutting edge 28 in a straight plane throughout its entire length and relieved rearwardly from such cutting edge as shown at 29, see Fig 2, so that only the cutting edge engages 25 with its companion cutter bar, when a comparatively thick cutter bar is employed.

30, 30 represent annular flanges at the ends of the cutter bar having a radius dimension substantially equal to the distance 30 of the cutting edge from the axial line of the cutter, upon which the ends of the stationary cutter travel, to prevent the same from moving beyond the cutting arc of the oscillating cutter. These flanges serve as 35 guides for the stationary cutter in its normal position.

31, 31 represent pintles projected beyond the flanges, providing an axis for the oscillating cutter. They are journaled in the 40 side frames 2, 3, and preferably project beyond the side frame 3, to fixedly receive the toothed quadrant 32, its teeth 33 being adapted to be intermeshed with the teeth 34 of the segment pinion 35 fixed upon the 45 shaft 20. The toothed intermesh is relatively arranged and timed to become effective during the inoperative interval of the feeding rolls when the gear 19 at its cut-away toothed portion is tangent with the 50 circumference of gear 18.

As shown, the oscillating cutter is operative toward the limit of rotation of the 55 crank handle in a paper feeding cycle, after the requisite feed of the paper. The oscillating cutter is rocked or rotated rearwardly to its normal position automatically, the spring 32' has one end thereof fixed to the side frame 3, with the opposite end to the arm of the quadrant, or toothed lever.

60 As shown in the drawings, the segmentally toothed pinion 35 has but two teeth, which in a feeding cycle with the crank handle moving toward the right, as shown by arrows, will not engage the teeth of the lever 65 32 until after the feed of the feeding rolls

has been discontinued. As soon as the teeth of the segmental pinion 35 pass the last tooth 33 or the lever 32, the lever will be free to be oscillated to its normal position. The normalizing movement of the oscillating cutter being in a direction of the feed or advance of the paper and therefore will not interfere with such advance, should a successive interval advance of paper quickly follow.

36 represents the stationary cutter having its cutting edge 37 disposed in a diametric plane longitudinally with the axis of the oscillating cutter and the rear portion thereof provided with relief. This cutter is 80 slidably mounted in ways formed in each of the side frames with a spring 36' housed in each of the side frames engaging the stationary cutter to urge the same downwardly toward the axis of the oscillating cutter. The tension of the springs can be adjusted by the screw 37.

The upper portion of the stationary cutter is arced or angled toward the tangent line of the feeding rolls so as to enable the 90 paper to be fed over the same and delivered from the machine and severed by pulling the same over the knife edge 38 of the housing 39, inclosing the feed rolls, or the paper could be severed manually by pulling the 95 same upwardly from one end against the cutting edge of the stationary cutter.

40 represents a table fixed to the side frames and projecting beyond the forward portion of the apparatus to receive the severed length, and the forward portion of the table may be provided with a notch, for readily grasping the paper.

41 and 42 represent pawl and ratchet mechanism for preventing reverse action 105 of a crank handle, the ratchet wheel 41 being fixed to shaft 20.

43 represents a lever one provided adjacent each of the side frames and pivotally mounted upon the axle or shaft 12 of the lower feed roll, one arm of each lever adapted to engage at opposite ends with the axle 15 of the upper feed roll for raising the same to release the frictional engagement of the feeding rolls and separate the same to 110 conveniently thread the paper between said shafts. The levers are actuated by rock shafts 44 manually accessible from the exterior of the machine by the lever arm 45.

The essential features to which my invention is primarily directed is in the provision of a pair of coacting cutters, one having oscillating motion, the second stationary relative to the oscillatory movement of its companion cutter but yieldingly urged toward the same, its cutting edge longitudinally diametric with the axis of the longitudinal spiral oscillating cutter, to provide a progressive continuous cutting action transversely across the paper, and when combined 125 130

with feeding instrumentalities operative at a timed interval in a propelling cycle.

The toothed lever 32 engages an adjustable stop to limit its normalizing movement, comprising an eccentric collar 46 adjustably secured to the side frame 3 by a screw 47, see Fig. 1. This also provides for the proper coöperation of the teeth 33 and 34 of the lever 32 and segment pinion 35.

10 Having described my invention, I claim:—

1. In a machine of the nature disclosed combining a pair of coacting paper feeding rolls having their peripheries yieldingly engaging each other, a pair of coacting cutter elements subsequently acting upon the paper after the advance of the paper has discontinued, said cutter elements comprising an oscillating cutter blade having its cutting edge longitudinally spiral and engaged with a non-rotative cutter blade in a longitudinal progressive action from one end thereof toward the other, a non-rotative cutter blade yieldingly urged toward the cutting edge of the oscillating cutter blade, with its cutting edge diametric with the axis of the oscillating cutter and means for restraining the movement of said non-rotative cutter toward said oscillating cutter.

2. In a device of the nature disclosed, combining a pair of paper cutting blades, one thereof having its cutting edge movable in an arc across the cutting edge of the second cutter blade, and longitudinally spiral from one end toward the other to produce a progressive cutting action, with the cutting edges of both coacting at a diametric line with the axis of said movable cutter and means for yieldingly urging one of said cutter members toward its companion cutter member to within predetermined limits for coöperation.

3. In a device of the nature disclosed, combining a pair of paper cutting blades, one thereof having its cutting edge movable in an arc across the cutting edge of the second cutter blade, and longitudinally spiral from one end toward the other to produce a progressive cutting action, with the cutting edges of both coacting at a diametric line with the axis of said movable cutter, means for yieldingly urging one of said cutter blades toward its companion to within predetermined limits for coöperation, and

means for oscillating said movable cutter blade.

4. A device of the nature disclosed comprising a pair of coacting cutter members, the one rotatable, and the second non-rotative having its cutting edge yieldingly urged in a diametric plane with the axis of said rotatable cutter member to within restraining limits for coöperation, and the rotatable member having its cutting edge longitudinally spiral and circumferentially movable to progressively engage in a tangent plane the cutting edge of said second cutter member.

5. A device of the nature disclosed combining a pair of coacting paper feeding rolls, a mutilated master gear for positively rotating said rolls, and producing a dormant interval in each cycle thereof, a crank handle for propelling said gear, a pair of coacting cutter members arranged in close proximity to said paper feeding rolls, one thereof rotative and the second non-rotative and yieldingly urged toward said rotative cutter member to within restraining limits for coöperation, and propelling means for said rotative cutter member connected with said crank handle operative sequentially and during the dormant interval of said feeding rolls.

6. A device of the nature disclosed combining a rotative cutter member having its cutting edge extended longitudinally with its axis, and a non-rotative cutter member yieldingly urged toward said rotative cutter member to a restraining limit for coöperation.

7. A device of the nature disclosed combining a rotative cutter member having its cutting edge extended longitudinally with its axis, a non-rotative cutter member yieldingly urged toward said rotative cutter member, and annular means upon said rotative cutter member engaging said non-rotative cutter member to restrain its movement to within a predetermined limit for coöperation.

In testimony whereof, I have hereunto set my hand.

ALBERT KRAUTH.
